UNITED STATES PATENT OFFICE

HECTOR RABEZZANA, OF FLINT, MICHIGAN, ASSIGNOR TO A C SPARK PLUG COMPANY, OF FLINT, MICHIGAN, A COMPANY OF MICHIGAN

SPARK PLUG

Application filed November 12, 1924. Serial No. 749,414.

My invention relates to spark plugs designed for use with internal combustion engines to ignite the combustible mixture supplied to and burned within the working cylinder thereof, and the principal object of the invention is to provide a spark plug having features of construction and arrangement of parts such that heat may flow from the insulating member of the plug to the shell or 5 casing, and from thence to cylinder wall or head of the engine more readily, that is, with less resistance to such flow of heat, than has heretofore been the case; to the end or with the result that the plug, and particularly the 10 insulating member thereof, will remain cooler than has heretofore commonly been the case. Any reduction in temperature of the insulating member, particularly at the exposed inner end thereof, secured in a spark plug lessens 15 the tendency to pre-ignition of the mixture during the compression thereof in the engine cylinder; and the more free flow of heat from the inner end of the plug secured in my improved spark plug lessens the tendency to pre-ignition when the engine is in operation. My 20 improved spark plug is especially adapted for use in racing automobiles the engines of which when driven at their maximum capacity operate much hotter than is ordinarily 25 the case in automobile engines, and in which service pre-ignition of the mixture is particularly liable to occur. As a matter of fact pre-ignition of the mixture is ordinarily the 30 most serious difficulty met with, and the most prominent single circumstance operating to 35 limit the temperature of operation of an internal combustion engine.

A further object of my invention is to provide a spark plug wherein the inner end of the insulating member which is exposed to the burning gases will be less liable to become cracked or broken, due to strains resulting from expansion of said inner end when the plug is in operation, than in prior 40 plugs; such expansion being obviously the more pronounced, and the harmful results thereof the more difficult to avoid and overcome in cases where the plug is used in an engine designed to operate at an inordinately 45 high temperature.

A further object of my invention is to provide a spark plug which will be more nearly gas tight, and in which there will be less leakage between the insulating member and the shell and central electrode than heretofore; 55 and other and further objects and advantages of my invention will be pointed out in the more full and complete explanation thereof hereinafter appearing.

The drawing accompanying and forming 60 a part of this specification illustrates the preferred embodiment of my invention; although the same may be embodied in various other forms, all of which I regard as included in my invention and in the patent to 65 be secured therefor so long as such variations and modifications come within the scope of the concluding claims; wherein the distinguishing features of my invention are particularly pointed out.

In the drawing:

Figure 1 is a view showing a spark plug made in accordance with my invention upon a central plane extending longitudinally thereof.

Figure 2 is a view showing a section upon a transverse plane indicated by the line 2—2, Figure 1, looking down.

Figure 3 is a view similar to Figure 1 but showing my invention as slightly modified as 80 regards certain parts and features thereof.

Figure 4 is a view showing a section upon a transverse plane indicated by the line 4—4, Figure 3, looking down.

Referring now to the drawing, the reference numeral 5 designates the external metallic shell or casing of my improved spark plug, the same having a threaded portion 6 which screws into a threaded opening in the cylinder wall or head of the engine with which the plug is used; said casing being hollow to provide a passage within which the insulating member 7 of the plug is held in any suitable way, as by an inturned flange 8 at the outer end of the shell which overlies a shoulder adjacent the upper end of the insulating member.

The passage within which the insulating member is located is shown as comprising an upper cylindrical portion 9 and a lower coni-

cal portion 10, and the insulating member as having correspondingly shaped portions as shown. The lower conical portion of the insulating member and the conical portion 10 of the passage in the casing are ground surfaces, in order to secure intimate contact between the two throughout a joint of large area; the final fitting of the parts to one another being preferably accomplished by 5 grinding (rotating) each particular insulating member in place within the shell with which it is to be used.

The comparatively extensive and large area of joint between the parts thus secured, together with the intimate contact between the parts due to the grinding, provides a joint which offers a minimum of resistance to the flow of heat from the inner end of the insulating member and central electrode of the 10 plug (designated by the numeral 11) to the casing thereof, and to the wall of the engine cylinder; and provides a plug which will operate cooler, and with less liability to pre-ignition of the mixture than has heretofore 15 commonly been the case. Obviously this result is dependent more upon the conical than upon the cylindrical portion of the passage within which the insulating member is contained; and the relative lengths of these parts 20 may be varied to a point where the cylindrical portion disappears, with a concomitant reduction in the resistance to the flow of heat from the insulating member to the shell and to the engine cylinder. Furthermore, and as 25 will be appreciated, the joint formed as aforesaid between the conical portion of the insulating member and the seat wherein it rests is one which will be unusually tight, and one wherein leakage of gas therethrough will be 30 effectively prevented; and that without the use of a gasket adjacent the inner end of the insulating member such as has heretofore 35 commonly been used in spark plugs.

The central electrode 11 extends through a 40 passage provided in the insulating member, and terminates adjacent the grounded or shell electrode 12 of the plug as heretofore. Said electrode, however, is made more massive than is usually the case, and is threaded and 45 screwed into a roughly threaded portion of the passage along which it extends; the threads being coated with a suitable cement before the electrode is screwed into place in order to secure a gas tight joint and a more 50 intimate contact between the parts which will offer a minimum of resistance to the flow of heat from the central electrode to the insulating member. The massive construction of the said electrode, however, provides a path 55 of low resistance for the flow of heat along the same and to its outer end where it is radiated directly into the surrounding atmosphere, and reduces materially the quantity of heat flowing to the insulating member, and 60 from thence for the most part to the shell of

the plug. The central electrode may have threaded end portions with an intermediate unthreaded portion as shown in Figure 1, or may be threaded throughout its entire length as shown in Figure 3. Both forms appear to be equally effective, although the latter is somewhat to be preferred as a manufacturing proposition.

The inner end of the insulating member which is exposed to the heat of the burning gases is provided with a conical chamber 13 the wall of which is inclined oppositely to the wall of the conical shell passage 10, and the inner end 14 of the insulated electrode 11 lies within this chamber in the assembled plug. This construction provides the usual dead gas chamber commonly present in spark plugs to prevent short circuiting at the spark gap; although it will be appreciated that the chamber herein is surrounded by an insulating wall provided by the lower end of the insulating member which feature secures a higher temperature at the spark gap, and a more effective burning away of carbon, oil, etc. from the terminals at the gap, than is the case in spark plugs wherein the outer wall of the dead gas chamber is a metallic wall integral with the shell or casing of the plug.

In order to prevent breaking or cracking of the inner end of the insulating member where its cross section is considerably reduced to provide the dead gas chamber 13 I reduce the diameter of said inner end slightly, as by grinding a circumferentially extending recess about such inner end, as indicated at 15 in Figures 1 and 2; the Figure 3 and 4 forms not having such a recess as the plug will operate satisfactorily without such a recess when the same is used in engines wherein 105 excessively high temperatures are not likely to occur. Plugs having such recesses are, however, preferred in services wherein excessive heating is to be expected, as in racing cars as hereinbefore explained.

The purpose of the recess 15 as explained is primarily to prevent breaking of the inner end of the insulating member by stresses resulting from expansion and contraction of the parts when the plug is subjected to inordinately high temperature, as hereinbefore explained, which it does by providing a sort of cushion between the parts which will yield under the stresses due to expansion and contraction of the parts, even though the recess 115 may become more or less filled with carbon deposited by the burning gases. Said recess, however, performs the further function of reducing the flow of heat from the chamber 13 to the metallic casing of the plug and to the cylinder wall, and thus secures a higher temperature and a more effective burning away of carbon deposit at the spark gap. As a matter of course such heat as cannot be confined to the vicinity of the gap, and which 120

cannot be prevented from flowing along the central electrode and insulating member, flows along said parts and is the more effectively dissipated by the various parts and features of the improved plug wherein my invention consists, as has hereinbefore been explained in detail.

Having thus described and explained my invention, I claim and desire to secure by Letters Patent:

10 In a spark plug, a unitary single piece hollow metallic shell or casing having an interior insulator receiving passage conical in form, and which passage is of least area at the inner end of the casing and becomes larger as the distance from said inner end increases; an insulating member formed separately from said shell and ground in place therein, and having a tapering portion which fits within 15 said passage and extends substantially to the inner end of said casing and which member is secured in place within said passage by an inturned flange at the upper end of said shell, said member having a chamber conical in 20 form in its inner end and the wall of which chamber is inclined opposite to the inclination of the adjacent conical wall of the casing aforesaid; an insulated electrode extending through a centrally arranged passage in 25 said insulating member and into said conical chamber; and a grounded or shell electrode carried by said external casing and arranged in sparking relation to the inner end of said insulated electrode.

30 In testimony whereof I affix my signature.
HECTOR RABEZZANA.
